UNITED STATES PATENT OFFICE.

JOSEPH AHRENS, OF BERLIN, GERMANY.

MACHINE FOR TREATING PEAT TO BE USED AS FUEL.

SPECIFICATION forming part of Letters Patent No. 657,907, dated September 18, 1900.

Application filed March 9, 1899. Serial No. 708,327. (No model.)

To all whom it may concern:

Be it known that I, JOSEPH AHRENS, a subject of the King of Prussia, residing at Berlin, in the Kingdom of Prussia, German Empire, 5 have invented certain new and useful Improvements in Machines for Treating Peat to be Used as Fuel, of which the following is a specification.

The object of this invention is a machine 10 for treating peat to be used as fuel.

Upon the accompanying drawings, illustrating this invention, Figure 1 is a side elevation of a machine, partially in section. Fig. 2 is a plan, the vertical borers not being 15 shown. Fig. 3 represents a cross-section on line *a a* of Fig. 1. Fig. 4 shows the drum for carrying the peat blocks with the tools by which the peat is acted upon in perspective.

The blocks of peat to be treated are periodically placed in a hopper *a*, so that they arrive upon a slide *b*, by the advance of which to the left the said blocks are brought under the action of a pair of saws *c*. The slide *b* receives a reciprocating motion from a lever 20 *e*, pivoted at *d*, which is connected at the top to the slide by the link *f* at *g*. Through the slotted part *h* of the lever *e* a pin *i* projects, which is secured to a sliding rod *k*, suitably fitted in bearings on the framework of the 25 machine and moved to the right by means of a cam *m*, fitted on the spindle *l*. By this arrangement the lever *e*, and thus the slide *b*, is moved from the position shown in Fig. 1 likewise toward the right. The return of the 30 slide into the position shown in Fig. 1 is effected by means of a cam *o* upon the spindle *n*, which presses against a pin or roller *p* and so moves the lever *e* toward the left. When the slide has been moved into the position 35 shown in Fig. 1, it arrives, with the block of peat, between a pair of saws *c*. The saws are secured on a common spindle *q*, which is rotated by means of bevel-gearing driven from a belt-pulley *s* and spindle *t*. When 40 the block of peat has been cut to the desired breadth by means of the pair of saws *c*, the slide *b* is moved, by means of the mechanism above described, toward the right, so as to arrive under the hopper *a* again, and the second block is dropped in, which is likewise moved to the left between the pair of saws *c*, 45 at the same time advancing the first piece of

peat, so that it arrives between a pair of saws *u*, by which it is cut to the desired thickness. This second pair *u* are blade-saws, as 55 will be seen from Figs. 1 and 2, and are reciprocated backward and forward in slides *v*, of dovetail form. The slides *v* are both connected to a rod *w*, which, receiving motion from an eccentric *a'* upon the spindle *t*, moves 60 the slides, and thus the pair of saws *u*, as before mentioned. Instead of blade-saws *u* circular saws can of course be used. As the block of peat is being cut to the desired thickness it passes gradually onto the drum *b'*, 65 which, as will be seen from Fig. 4, is provided with a number of grooves *c'*—as, for example, six or eight—each of which corresponds to the breadth of the cut block of peat. This drum *b'* is supported upon an 70 axis *d'*, which is fitted in bearings on the framework of the machine. When the block of peat arrives in one of the grooves *c'*, it rests beneath a group of borers, which are rotated by a belt-pulley *e'* in a suitable manner. 75 These borers *f'* are fitted in a common bearing-block *g'*, to which is connected a lever *i'*, pivoted at *h'* and connected at one end by a rod *k'* with a lever *m'*, having its fulcrum at *t'*. The arm *m'* is acted upon by a cam *n'* 80 upon the spindle *l*, which raises the lever *m'* in rotating, and thus by means of the rod *k'* so moves the lever *i'* that the other end depresses the bearing-block *g'* with the borers *f'*, by which means the block of peat beneath 85 the borers is perforated. As soon as the borers *f'* have passed through the block of peat another double-armed lever *o'* is so actuated from the spindle *l* by means of a suitable cam *o'* that the plate *p'* is depressed. This plate 90 carries a number of rods which slide in the interior of the hollow cylindrical borers *f'*, and upon being depressed with the plate *p'* eject the pieces of peat out of the borers *f'*, so that the openings of the borers are again 95 free. In order to avoid the possibility of the holes thus made in the block of turf from remaining stopped, it is of advantage to so perforate the drum *b'* that the pieces acted upon by the rods fall into the drum, from whence 100 they are laterally led off. When the borer is permitted to rise to its original position by the further rotation of the cam *n'*, the drum *b'* is moved one division farther, so that an

empty groove or recess arrives in the path of a second block of peat and the first block arrives before another group of borers, which are horizontally arranged. This motion of the drum is effected by means of a pawl q' , which, guided in a suitable manner, is raised by a cam r' upon the spindle s' , a spring t^3 keeping the pawl q' continuously in engagement with a ratchet-wheel w' . The first block of peat having arrived at the borers $v' w'$, which are arranged opposite to each other, the group of borers v' on the left are moved to the right until the ends have penetrated through half the length of the block. This motion is transmitted from the spindle l , on which a rod a^2 is eccentrically fitted, the front end of which engages a lever b^2 , pivoted at d^2 . This lever b^2 is so connected with the supporting-frame f^2 of the group of borers v' by means of a link e^2 that the lever b^2 receives a backward-and-forward swinging motion about d^2 , and the borers v' , which are rotated by the belt-pulley g^2 and spindle h^2 , are pressed into the block of peat or pulled out of the same. After the block of peat has been bored out from the left to the right to half of its length in the manner above described the group of borers v' retreats, whereas the group w' advances. This latter group w' , like the group v' , receives a backward-and-forward motion from a lever b^2 , which is connected by a link e^2 with the borers w' , in order to complete the horizontal perforations commenced by the borers v' . The swinging motion of the lever b^2 is not effected by an eccentric bearing, but by a curved groove i^2 , arranged in a cylinder k^2 on the spindle s' . When the borers v' and w' have both been withdrawn from the perforations back to their normal position, the drum b' is again somewhat rotated by means of the pawl q' , so that the perforated block of peat is now brought to a set of saws. This set of saws consists of six blades, of which the two outer, l^2 , serve for cutting the block of peat to the prescribed length, whereas the shorter saws m^2 are arranged to cut slits in the block in order to enable the convenient breaking up of the block into pieces. For this purpose the drum b' is

provided with corresponding grooves n^2 . By the further intermittent rotation of the drum b' all the blocks of peat arriving on the slide b are subjected in the prescribed order to the operations above described, whereas the block first treated, prevented by a guard o^2 , Fig. 55 4, from falling out, is conducted to an exit-opening, through which it falls as soon as the groove in the drum containing it arrives perpendicularly beneath the axis d' . The spindle s' , which reciprocates the borers w' , receives its motion from miter-gearing p^2 , the one miter-wheel of which is fitted on the spindle n , which is driven by means of worm r^2 from the spindle s^2 through the agency of the belt-pulley t^2 . 65

It is not absolutely necessary that the motion of the separate parts be effected by means of the levers above described, and shown in the drawings, as any other lever mechanism may be used. 70

What I claim, and desire to secure by Letters Patent of the United States, is—

1. In a machine for treating peat, the combination of a slide upon which the blocks of peat are fed, a pair of saws to trim two sides 75 of the block, another pair of saws to trim two other sides of the block, a rotating drum beyond the saws provided with seats receiving the trimmed block and boring devices adjacent to the drum for perforating the block, 80 substantially as described.

2. In a machine for treating peat, the combination of a slide upon which the blocks of peat are fed, a pair of saws to trim two sides 85 of the block, another pair of saws to trim two other sides of the block, a rotating drum beyond the saws and provided with seats receiving the trimmed block, boring devices adjacent to the drum for perforating the block, and a set of saws adjacent to the drum to cut 90 slits in the block.

In testimony whereof I have hereunto set my hand in the presence of two witnesses.

JOSEPH AHRENS.
